SHUTTLE-GUARD DEVICE FOR SHUTTLES WITHOUT THREADING DEVICES FOR AUTOMATIC LOOMS

Application filed August 14, 1929, Serial No. 385,701, and in Switzerland February 2, 1929.

This invention relates to shuttle guard devices, more particularly for automatic looms for shuttles of the kind not provided with a threading device for checking the shuttle on entering the box.

The known shuttle-guard devices for automatic looms, generally in combination with guard shears, touch upon the side of the bobbin head of the shuttle at the shuttle point and determine whether the shuttle is introduced into the shuttle-box a sufficient extent to enable the bobbin-changing mechanism to be set in motion. Thus the control of the position of the shuttle is only of the one-sided kind. Therewith there is no arrangement controlled by the shuttle penetrating too deeply into the box; thus there is no device for causing an inaccuracy in the position of the shuttle of at the most 1 cm. to be compensated by the bobbin being pressed by the hammer upon a sloping surface in the shuttle so that this wedge-action brings the shuttle into the correct position. This latter process has the disadvantage that the hammer is forced and the wooden bobbins must be provided at the head end with a metal coating in order to be able to withstand this treatment. If, in consequence of the wearing out of the shuttle-driver, the shuttle goes still deeper than the admissible amount of 1 cm. into the box, it may easily lead to the breaking of the hammer.

The shuttle-guard device according to the present invention is characterized hereby, that a transverse opening arranged on the shuttle co-operates with a wedge-piece movable backwards and forwards, in such a manner that by the action of this wedge-piece a false position of the shuttle of about 1 cm. to the left or right is automatically corrected, but with a greater false position the changing of the bobbin is interrupted.

In the accompanying drawing wherein an approved embodiment of the invention is illustrated:

Fig. 1 is an elevation of the improved shuttle guard device;

Fig. 2 is an end view thereof;

50 Figs. 3, 4 and 5 are plan views of the de-

vice including the shuttle and showing parts in different positions;

Figs. 6 and 7 are sectional views showing means for lifting the box-tongue from the shuttle, such means being shown in two positions;

Fig. 8 is an elevation similar to Fig. 1, but showing the shuttle in a position such that the wedge-shaped piece 3 cannot enter the opening of the shuttle;

Fig. 9 is a plan view corresponding to Fig. 8; and

Fig. 10 is an end view of the parts shown as represented in Fig. 8.

Referring to the drawing, on the side of the bobbin point the shuttle 1, which has no threading device, is provided with an opening 2 passing right through into which, on the shuttle correctly entering the shuttle-box (Figs. 1, 2 and 5), there can enter without obstruction, that is without displacement of the shuttle, the wedge-shaped end 3 of a bell-crank lever 6¹ rotatable about a rod 4, which remains on the one hand under the pull of a spring 5 and thereby is turned away from the shuttle 1 and on the other hand by a rod 6 influenced by the weft-feeler, the bell-crank lever 6¹ being moved against the shuttle at the moment of changing the bobbin. In the position of preparation of the bell-crank lever 6¹ for the changing of the bobbins the hammer latch 7 which is connected therewith by a rod 6² is raised into the position shown in Fig. 2, so that the shuttle box plate 8 can engage in the latch 7 and ~~actuate~~ the hammer 9 for the purpose of changing the bobbins.

If the shuttle after entering the shuttle box takes up such a position (Figs. 8, 9 and 10), that the wedge-piece 3 cannot enter into the opening 2 of the shuttle 1, then the wedge-piece 3 is pressed back by the shuttle and the bell-crank lever 6¹ is rotated so that the latch 7 is lowered and therewith brought outside the path of swing of the push piece 8 and the change of the bobbins is thus interrupted (Fig. 10).

If the position of the weft shuttle which has entered deviates only about 1 cm. to the left or right from the correct position

in the shuttle box (Figs. 3 and 4), the wedge-piece 3, on the swing to the right of the bell-crank lever 6¹ under the influence of the weft-feeler, brings the shuttle 1 into the correct position (Fig. 5) for inserting a fresh bobbin through the hammer 9 into the shuttle. In order to facilitate this displacement of the shuttle, the shuttle box tongue 10 (Figs. 6 and 7) is lifted from the shuttle by a roller 11 carried by the lower end of a two-arm lever 14, rotatable on the lay 12 about a pivot pin 13 running upon a stationary sliding surface 15.

What I claim is:

15 1. In a shuttle-guard device for shuttles without threading device, for automatic looms, the combination comprising a shuttle having a transverse-opening, a wedge-piece capable of entering into the said opening 20 when the shuttle is in its correct position and of automatically correcting an error of position of the shuttle of about 1 cm. to the left or right, means connected to the weft-feeler to move the wedge-piece against the shuttle in the moment of changing the bobbin and means interposed between the said wedge-piece and the bobbin changing hammer to prevent changing of the bobbins in the event of a greater error of position of 25 the shuttle.

2. In a shuttle-guard device for shuttles without threading device, for automatic looms, the combination comprising a shuttle having a transverse-opening, a wedge-shaped piece capable of entering into the said opening when the shuttle is in its correct position and of automatically correcting an error of position of the shuttle of about 1 cm. to the left or right, a bell-crank lever carrying 30 the said wedge-piece and being connected on the one hand to a spring and on the other hand to the weft-feeler and a mechanical connection between the said bell-crank lever and the bobbin changing hammer to interrupt the change of the bobbins in the event of a greater error of position of the shuttle.

3. In a shuttle-guard device for shuttles without threading device, for automatic looms, the combination comprising a shuttle 50 having a transverse-opening, a wedge-piece capable of entering into the said opening when the shuttle is in its correct position and of automatically correcting an error of position of the shuttle of about 1 cm. to the left or right, means connected to the weft-feeler to move the wedge-piece against the shuttle in the moment of changing the bobbin, means interposed between the said wedge-piece and the bobbin changing hammer to prevent changing of the bobbins in the event of a greater error of position of the shuttle, a two-armed lever pivotally supported by the lay to swing about a horizontal axis and a stationary cam surface capable of acting 55 upon the said lever to lift the shuttle-box

tongue from the shuttle and to facilitate the displacement of the latter.

In testimony whereof I have affixed my signature.
